(57) **CLAIM**

The ornamental design for a camera kit bag, as shown and described.

DESCRIPTION

FIG. 1 is a left front perspective view of a camera kit bag showing my new design.

FIG. 2 is a top plan view thereof.

FIG. 3 is a right side elevational view thereof; the left side view being a mirror image thereof.

FIG. 4 is a front elevational view thereof.

FIG. 5 is a rear elevational view thereof; and,

FIG. 6 is a bottom plan view thereof.

The portions of the design shown in phantom lines are for demonstrating a position of a top flap of the camera kit bag in an open position and form no part of the claimed invention.
